UNITED STATES PATENT OFFICE.

ORION W. NUNN, OF DENVER, COLORADO, ASSIGNOR TO LANDIS MACHINE COMPANY,
OF ST. LOUIS, MISSOURI, A CORPORATION OF MISSOURI.

BUTTON-STAPLING MACHINE.

1,132,112.

Specification of Letters Patent. Patented Mar. 16, 1915.

Application filed January 21, 1914. Serial No. 818,448.

To all whom it may concern:

Be it known that I, ORION W. NUNN, a citizen of the United States, residing at the City of Denver, county of Denver, State of Colorado, have invented a certain new and useful Improvement in Button-Stapling Machines, of which the following is a full, clear, and exact description, such as will enable others skilled in the art to which it appertains to make and use the same, reference being had to the accompanying drawings, forming part of this specification, in which—

Figure 1 is a side elevation of my improved stapling machine. Fig. 2 is a sectional elevation taken on line 2—2 of Fig. 7. Fig. 3 is a side view of the button container. Fig. 4 is a detail plan view of portions of the wire cutting and driving mechanism. Fig. 5 is a vertical section of the same taken on line 5—5 of Fig. 4. Fig. 6 is a vertical section taken on line 6—6 of Fig. 4. Fig. 7 is a plan view partly in section of the entire machine. Fig. 8 is a detail front view illustrating portions of the wire and button feeding and holding mechanism. Fig. 9 is a sectional elevation on line 8—8 of Fig. 7. Fig. 10 is a detail side view looking at the left hand side of the machine. Fig. 11 is a section taken on line 11—11 of Fig. 10. Fig. 12 is a detail of a button tube.

My invention relates broadly to shoe machinery, and more specifically to an improved machine for stapling buttons onto shoes.

The machine is of that design wherein wire is cut from a continuous strand, fed to a button which is guided to proper position, shaped into a staple, and finally driven and clenched.

The particular object of my invention is to provide a machine having an improved feeding and feed regulating device whereby the wire will be fed so long as buttons are in proper position to receive the same, but will not be fed unless there is a button in proper position. The purpose of this is to prevent waste of wire and injury to a shoe by uselessly driving in it staples without buttons.

A further object of my invention is to provide an improved button and wire holding arrangement whereby the button shall be held in proper position to be engaged by

the wire, and the wire held in proper position for cutting, shaping and driving.

With these and other objects, which hereinafter will be pointed out or obvious, in view, it will be understood that my invention contemplates a suitable base 1 which may be supported on any proper support 2, and which provides attachment and support for brackets 4. Upon brackets 4 is supported a slotted track bar 5 in which operates a suitable carriage 6. Upon the carriage 6 are carried journal plates 7 in which is journaled shaft 8. The shaft 8 provides a support for suitable cylinders 9 of a particular form which act as containers for buttons and have special features which operate to feed the buttons to other mechanism. As will be best understood by reference to Figs. 2, 3 and 7, the journal plates 7 act as closures for one end of each of the cylinders, while the other end of each of the cylinders is open. The cylinders are mounted for rotary movement on shaft 8 independently of one another, the mounting being by means of a journal 10 supported by suitable webs 11 from the inner walls of the cylinders. Adjacent its open side, each cylinder is provided with a series of vanes or feeding buckets 12 which curve inwardly from the open end of the cylinder. About the perimeter of each cylinder are provided teeth 14 by means of which the cylinder is rotated. When the cylinder contains shoe buttons, rotation thereof causes the vanes or buckets 12 to pick up the buttons and feed them toward the open end of the cylinder, meanwhile carrying them upwardly with the rotation of the cylinder and discharging them when they have been elevated to an extent somewhat past the horizontal axis of the cylinder.

Mounted on the carriage adjacent the open end of each cylinder, is a guide tube 15 which is inclined downwardly and forms a conduit for buttons from the cylinder to the driving mechanism. The bottom wall of this guide tube is slotted to receive the eyes of the shoe buttons, and where it crosses the end of the cylinder it is open at the top for a part of the way, as is best illustrated in Figs. 2 and 7. The slot 15a of the bottom wall is continuous across the cylinder. A turning plate 16 is placed over the bottom wall of the guide tube, and adjacent the end of the same, the said wall is narrowed by

having a portion 15^b thereof cut out adjacent the open end of the cylinder. As the buttons lifted by the vanes are thrown out onto the open portion of the guide tube, they slide down toward the end of turning plate 16. Such buttons as are sliding with their eyes in slot 15^a will pass under turning plate 16. Such as slide downward in other positions, will not be able to pass underneath turning plate 16, and will be deflected by the oblique end thereof off of the guide tube at the cut out place 15^b, and will fall back into the cylinder. Thus, all buttons which are fed to the stapling mechanism will be presented in the same position, to wit, with their eyes downward and the openings of the eyes sidewise or transversely of the guide tube. Auxiliary supply tubes 17 may be mounted on the carriage, such tubes being filled by hand, and being adapted to carry buttons of exceptional form or kind which are not frequently used. The supply tubes and the guide tubes are of just sufficient length to reach to the handling tube 18, and the conduit openings and slots 15^a of each of the guide tubes and supply tubes are adapted to register with the conduit and a slot 18^a of the handling tube. The conduits of the guide and the supply tubes are preferably closed by stop latches 20 which may be swung down to prevent buttons sliding out. All of the cylinders with their guide tubes, and the supply tubes, being mounted upon the traveling carriage, any one of the guide tubes or supply tubes may be positioned so that it will feed buttons to the handling tube by simply shifting the carriage in the keyway of the track bar 5. In the keyway is positioned a pin 21 which is operable by lever 22 against the influence of spring 24, which pin is adapted to coöperate with the openings 25 in the carriage to secure the carriage in proper position with the selected guide or supply tube in register with the handling tube.

As will be understood by reference to Figs. 9, 10, and 11, the handling tube 18 is equipped with a selecting mechanism adapted to feed the buttons one at a time to the driving mechanism. This selecting mechanism comprises a pair of pallets 26 and 26', and these are operated by a throwing cam 27 so that they are interposed alternately in the path of buttons in the handling tube 18. The pallets 26 and 26' are spaced apart a distance suitable for the reception of a single button, the result of which disposal and their alternate operation is to select and feed one button at a time. The lower end of the handling tube 18 is open and is provided with a pair of antennæ 28, which are of spring metal and which operate to hold the button in position to have the wire fed through the eye thereof, and which operate 65 to retain the button in its position until it is

forcibly withdrawn from them in the driving operation.

The handling tube 18 is supported on a frame 29 carried on the base 1, and a portion of this frame also forms the horn 30 in which is carried an anvil 31. Anvil 31 is adjustable by screw 33 toward and from the driver for the purpose of providing for different thicknesses of leather and insuring proper clenching. In the frame 29 is journaled the driving shaft 32. Driving shaft 32 has another bearing 34 also supported on the base 1. Rotation of driving shaft 32 is accomplished by operation of the treadle 35 which draws down bar 36 against the influence of the strong spring 37. The upper end of bar 36 is connected to the crank arm 38 which is pinned to driving shaft 32, so that downward movement of bar 36 rotates driving shaft 32 toward the front of the machine. Driving shaft 32 carries a disk cam 39 which operates a lever 40 pivoted at 41 on the bearing 34. The lever 40 operates a shuttle bar 42 which reciprocates longitudinally in the bearings 42' and carries at 43 its left hand end a tension device 44. The tension device 44 frictionally engages wire carried on the spool 45 to feed it to the cutters and the driver. The wire is fed through a hole 46 in a guide frame 47 just below the end of handling tube 18 and in line with the opening of the eye of a button B held by the antennæ 28. The end of the wire abuts against the side of a guide frame 47^a. A cutter and former operates between guide frames 47 and 47^a, the same being best illustrated in Figs. 4 and 5. This cutter and former has the legs 48 and 48^a which slide on guide frames 47 and 47^a respectively. The edge of the leg 48, coöoperating with the edge of the hole 46 in the guide frame 47, operates to shear off the length of wire measured between the inside of guide frame 47 and guide frame 47^a. Grooves 48' formed in the ends and inner faces of legs 48 and 48^a engage the length of wire cut off and hold it in proper position while it is being shaped over a mandrel 49 by the continued forward movement of legs 48 and 48^a which pass on either side of mandrel 49 and bend the wire about the same, thus forming a staple having its points directed toward the anvil 31 and having the button strung on the curved cross-piece connecting the legs of the staple. The mandrel 49 is then withdrawn from the path of the staple, the staple meanwhile being held by the notches 48'. After the mandrel 49 is withdrawn, the legs 48 and 48^a carry the staple, together with the button, forward until the ends of the staple are almost in contact with the work supported on the anvil 31. When the button and staple have thus been positioned for driving, the driver 50 comes down rapidly and drives and clenches the staple. 130

The middle portion of the end of the driver 50 is hollowed out to accommodate the eye of the button. These several operations are accomplished on the downward stroke of 5 the treadle. When the treadle is permitted to return under the influence of the heavy spring 37, the driver 50 is first withdrawn, followed by the shapers 48 and 48^a and then the mandrel 49 is raised into its elevated 10 position. At almost the end of the upward stroke of the treadle, the shuttle bar 42, which is retracted at the first downward movement of the treadle, returns leftwardly feeding a new length of wire through the 15 wire hole 46. The mechanisms by which these various movements of the shapers, the driver and the mandrel are accomplished will be best understood by reference to Figs. 2, 4, 5 and 6.

20 In suitable bearings in frame 29 slide the rack bars 51 to which are secured a yoke 52. Formed integral with this yoke 52 is a slotted bearing portion 54, and to this bearing portion is secured the driver 50. Consequently, upon forward or downward movement of the racks 51, the driver 50 comes downward and drives the staple. As is best shown in Fig. 6, the yoke 52 and bearing portion 54 are slotted to accommodate 25 the slideable bars 55 which carry at their lower ends the shaping members 48 and 48^a and which are at their upper ends connected to a bracket 56. This bracket 56 is secured to lower rack bars 57 which slide 30 in suitable bearings in frame 29. By virtue of these connections, it will be understood that while rack bars 57 travel downwardly, they carry with them the shaping members 48 and 48^a, which, as above described, operate to cut off and shape the wire about the 35 mandrel 49 and then carry the staple with its button into driving position. Mounted on shaft 32 at either side of frame 29 are irregular pinions 58 each having a series 40 of teeth 58^a which coöperate with one of rack bars 51, and a series of teeth 58^b which coöperate with one of rack bars 57. The relationship is such that rack bars 57 are actuated before rack bars 51 are, and therefore, shaping members 48 and 48^a are actuated 45 before the driver 50. One of pinions 58 carries a tripping lug 59 which, on forward rotation of shaft 32, rocks rocking cam 27 to release the button held between pallets 26 and 26' so as to permit its sliding down to position between antennae 28. Upon reverse movement of shaft 32 and rack 51, rocking cam 27 is returned so as to raise pallet 26' and lower pallet 26 by a pin 55 51' which is carried on one of rack bars 51. The mandrel 49 is lowered and raised by a pair of tripping fingers 60 and 60' which are carried on operating bar 36. These tripping fingers coöperate with one arm 61^a of a bell crank which is pivoted to the base 1 at

61, and the other arm 61^b of which is connected to mandrel 49 by a pair of links 62. Upon downward movement of operating bar 36, tripping finger 60 engages the arm 61^a, and, rocking the bell crank downward, 70 draws mandrel 49 down. Upon the return upward of operating bar 36, tripping finger 60' engages arm 61^a, and rocking the bell crank upward, moves mandrel 49 upward. Finger 60 abuts against the base 1 at the end 75 of the upward stroke of the bar 36, and forms a stop which prevents the transmission to the mechanism of violent thrusts occasioned by the forcible return of bar 36. To one of pinions 58 is pivoted one end of 80 a link 64, the other end of which is pivoted to a bell crank 65. The bell crank is pivoted on the frame at 65^a and has its other arm pivoted to a dog 66 mounted on frame 63 by a slot and pin connection. The nose 85 of dog 66 is adapted to coöperate with the teeth 14 of the cylinder positioned to feed buttons to handling tube 18, and upon forward rotation of shaft 32, link 64 and bell crank 65 push dog 66 upwardly so that it 90 engages one of teeth 14 and rotates the cylinder a few degrees.

In Figs. 8 and 9 is illustrated a controlling device for the wire feeding operation. It will be understood that the tension device 95 44 does not tightly clamp the wire, but simply engages it frictionally so as to feed it forward through the opening 46 when the passage of the wire therethrough is not obstructed. When the wire is held against 100 movement in either direction, the tension device 44 slides upon it without feeding it. The means which prevents the retraction of wire on the back stroke of the shuttle bar 42 is the detent 68 which is pivoted on the 105 support of the handling tube and has a toothed end 68^a adapted to contact with the wire. The teeth are directed in the direction of travel of the wire so that they do not engage the wire in its forward feeding movement, but bite into the wire when it tends to move backward. This detent 68 is spring pressed into engagement with the wire by a leaf spring 69. This prevents the wire being retracted upon the rearward 110 stroke of shuttle bar 42.

Means is provided for preventing the forward feeding of the wire, if, for any reason, a button is not in position between the antennae 28 before the beginning of the forward movement of shuttle bar 42. The purpose of this is to prevent wire being fed, and a staple formed and driven without carrying a button. This means comprises a stop lever 70 which is pivoted at 71 and has a laterally projecting lug 72 between its lower end and its pivot point, which lug is pressed downward by a leaf spring 74. The tendency of the pressure of leaf spring 74 on lug 72 is to swing the lower end of lever 70 125 130

downward. Stop lever 70 has a button engaging finger 70^a and a stop finger 70^b. The former lies in the path of buttons fed to the antennae 28, and the latter is adapted to swing downward across the wire opening 46 so as to close the same. A sliding pin 75 is seated in the support of feeding tube 18, and its upper end 75^a cooperates with lug 72 on lever 70. The lower end of pin 75 lies in the path of one of rack bars 51 which has its lower end beveled off to form a cam face. Upon the downward stroke of rack bars 51, this cam face engages sliding pin 75, and pushes it upward, thereby raising the lower end of lever 70. This releases the button held under the button engaging finger 70^a permitting it to be carried away by the shapers 48 and 48^a to be driven. Until nearly the end of the upward movement of rack bars 51, lever 70 is thus held elevated, permitting a new button to be fed to position between antennae 28. If no button has been fed to such position, lever 70 having nothing to stop it will swing downward to the full extent of its movement, which will interpose stop finger 70^b in front of the wire opening 46. Consequently, upon the subsequent forward movement of shuttle bar 42, the wire will not be fed into the path of the cutters and shapers 48 and 48^a, and therefore, no staple will be formed and driven at that operation of the machine. This prevents waste of wire and time, and injury to the shoe by uselessly driving staples without buttons.

It will be understood that the cylinders 9 are interchangeable, and that the button supply tubes 17 are interchangeable, so that various kinds or sizes of buttons may be used, filled tubes or cylinders of the various kinds of buttons being kept ready for use so that they may be substituted when desired. The cylinders are placed on the machine by unscrewing the shaft 8 and withdrawing it to an extent sufficient to permit the removal and insertion of a cylinder. Or a cylinder may be slipped on at the end of shaft 8. The supply tubes 17, as illustrated in Fig. 12, are mounted on depending lugs 40 50 55 13 which have apertures which are slipped over the end of shaft 8, and notches which engage pins 23 on carriage 6 to hold the tubes in proper position. It is obvious that instead of depending upon the journal plates 7 as closures for the cylinders, the cylinders may be formed with one end closed.

From the foregoing, it will be obvious that my invention comprises an improved form 60 of button staple forming and driving machine employing a novel form of button and wire feeding and controlling mechanism, and a novel and improved arrangement of operating parts.

65 I am aware that various modifications in

the device shown and described, may be made, without departing from the spirit of my invention, and therefore, it is not my intention that my invention be construed as limited to the specific form shown.

What I claim is:

1. In a button stapling machine including a button feeding mechanism, wire feeding mechanism, and staple forming and driving mechanism, a wire feed controlling device, 75 certain operations of which are controllable by a button fed to the forming mechanism, said device including means adapted to engage the wire for preventing wire being fed by the wire feeding mechanism when no button has been fed. 80

2. In a button stapling machine, the combination of button feeding mechanism, wire feeding mechanism, and a device adapted to be interposed in the path of the wire 85 for controlling the wire feed, the operation of said device being dependent upon the presence of a button in position to be stapled.

3. In a button stapling machine, the combination of button feeding mechanism, wire 90 feeding mechanism, forming and driving mechanism, and a stop device rendered inoperable by the button in driving position and adapted to engage the wire to prevent the wire feeding operation when no button 95 is in driving position.

4. In a button stapling machine, the combination of button feeding mechanism, wire feeding mechanism, and a stop device adapted to engage a button fed by the former and 100 with wire handled by the latter.

5. In a button stapling machine, the combination of button feeding mechanism, wire feeding mechanism, and a stop device adapted to engage a button fed by the former or 105 wire handled by the latter, the engagement of said device with a button precluding its engagement with the wire.

6. In a button stapling machine, the combination of button feeding mechanism, wire 110 feeding mechanism, means for holding a button while wire is being inserted through the eye thereof by the latter, a stop device adapted to engage a button held by said means, and means for rocking said stop device into 115 and out of engagement with buttons fed successively to said holding means, said stop device having a portion adapted to hold the wire to prevent the feeding of wire by said wire feeding mechanism. 120

7. In a button stapling machine, the combination of button feeding mechanism, wire feeding mechanism, including a reciprocating wire engaging member, a button holding means adapted to hold a button in position 125 to receive wire from said wire feeding mechanism, and a stop member adapted to prevent the feeding of wire by said wire feeding mechanism while permitting reciprocation of the latter, said stop member having a por- 130

tion adapted to engage a button held by said holding means for the purpose described.

8. In a button stapling machine, the combination of button feeding mechanism, a wire feeding mechanism adapted to feed wire intermittently, and a stop device whose operation is controllable by a button in setting position; said stop device being operable to prevent feed of the wire during a feeding movement of the wire feeding mechanism.

9. In a machine of the class described, the combination of an intermittent wire feeding

mechanism, a stop device adapted to prevent feed of the wire during a feeding movement 15 of the feeding mechanism, and a button feeding mechanism adapted to feed buttons to inhibit the operation of said stop device.

In testimony whereof I hereunto affix my signature in the presence of two witnesses, 20 this 15th day of December, 1913.

ORION W. NUNN.
